UNITED STATES PATENT OFFICE.

ISAAC P. CADMAN, OF BELOIT, WISCONSIN, ASSIGNOR OF ONE-HALF TO
GEORGE L. CADMAN, OF SAME PLACE.

WIND-WHEEL.

SPECIFICATION forming part of Letters Patent No. 328,836, dated October 20, 1885.

Application filed September 8, 1884. Serial No. 142,501. (No model.)

To all whom it may concern:

Be it known that I, ISAAC P. CADMAN, of Beloit, in the county of Rock and State of Wisconsin, have invented certain new and useful Improvements in Windmills, of which the following is a specification.

My invention relates to geared windmills, and particularly to the construction of the wheel proper, to automatic governing mechanism therefor, and to a device for overcoming side draft.

Figure 1 is a side elevation of the windmill with the cap or dome in section and a portion of the wheel broken away to show the construction more clearly; Fig. 2, a vertical section through the dome on the line $\alpha\alpha$ of Fig. 1; Fig. 3, a horizontal section on the line yy of Fig. 1; Fig. 4, a horizontal section on the line zz of Fig. 1; Fig. 5, a face view of the wheel; Figs. 6 and 7, views illustrating modifications of the equalizer for overcoming the side draft.

The objects which I seek to attain by my invention are to prevent side draft, or the swinging of the wheel out of the wind, to perfectly regulate the mill, and to simplify and strengthen the construction of wheels having pivoted blades, through the adjustment of which the speed of the wheel is regulated and controlled.

In all geared windmills there is a constant tendency of the wheel to work itself out of the wind. This I obviate by an arrangement of parts illustrated in Figs. 1, 2, and 4, in which A indicates a frame or tower provided at its upper end with a circular cap, B, having a vertical face, a , and C the rotary head or shell of the mill, containing the gearing and the governing devices, provided with front and rear arms, D and E, the former to support the wheel-shaft F and the latter for the attachment of the rudder-vane G. The shell will be furnished with a door or opening to give access to the interior.

H indicates the wind-wheel, secured upon the front end of shaft F, which shaft is made of tubular form to permit the passage through it of a governing-rod, hereinafter referred to.

I indicates the vertical or driven shaft of the mill, provided with a bevel-gear, J, which

meshes with and receives motion from a like gear, K, on the inner end of the wheel-shaft F.

The wheel is of course free to swing with shell or head C, which rests upon the stationary cap B, as usual, and is carried and held to the wind by the rudder or tail vane G. Whenever the wind is light, or the resistance offered by the driven machinery is considerable, there is a strong tendency of the wheel to work itself out of the wind, pinion or gear K of the wheel-shaft traveling around the axis of gear or pinion J, which wheel becomes stationary, or practically so, whenever the resistance offered by the driven machinery equals or exceeds the power of the wind acting upon the rudder-vane, and thus balances or overcomes the action of said vane. To prevent this action the rotary head C of the mill is provided with a lever, b, which passes from the center of the shell outward to a point slightly beyond its exterior wall, the lever being pivoted at a point, c, in the shell, as shown in Fig. 3.

To the outer end of the lever is pivoted a curved bar, d, near one end of the latter, which bar is furnished at its ends with rollers e, to bear against and travel upon the upright face a of the fixed cap B, so that the bar shall be kept in a given position relatively to the face of said cap, yet move freely about the same as the head or turn-table C rotates.

The inner end of lever b carries or is fashioned into a bearing, f, for the upper end of the shaft, which is the only bearing provided for said end of the shaft.

As the gear-wheel K and wheel H rotate always in one and the same direction, said gear, acting upon gear J, tends constantly to crowd the latter away before the advance of that side of the gear K meshing with it, being the lower side, as shown in the drawings. Thus, assuming that the wheel H and gears J K rotate in the direction indicated in Fig. 3, the gear J will be constantly crowded in the direction indicated by the double arrow in said figure.

The pivotal connection of the lever b and bar c forms an abutment for the lever, and just in proportion to the force of the lateral pressure upon the vertical shaft, and upon the

end of lever *b*, said force will be felt at its fulcrum *c*, or the point where the lever is pivoted to the rotary head or turn-table *C*, but in an opposite direction to the force exerted by the 5 shaft through gear *K*. As the shaft *F* and lever *b* are both fulcrumed in the turn-table *C*, and the forces are exerted at those points in opposite directions, the effect will be to create an opposing force at the fulcrum of the lever 10 *b*, which will neutralize the action of the forces exerted at the bearing of the shaft *F*. In this way the side draft is completely neutralized and overcome.

It is not essential that the equalizer be constructed and applied in the precise form illustrated in Figs. 1, 2, and 4; but the same principle may be embodied in various equivalent forms, two of which are illustrated in Figs. 6 and 7.

20 In Fig. 6 the lever *b* has its outer end connected with a brace-link, *z*, which is formed with a collar to encircle the wind-wheel shaft and to abut against the rear face of the hub of said wheel. In this case the wind-pressure 25 against the face of the wheel is made the rebutting pressure against the side action of the vertical shaft, which throws the combined pressures upon the pivot *c*. As the power of the wind-wheel is only a percentage of the 30 pressure of the wind on the face of the wheel, the force exerted against the collar of the brace-link at the hub of the wind-wheel will always be greater than that exerted on the shaft or inner end of equalizer at *f*.

35 Fig. 7 shows the same device in substantially the same form, but employing a lateral or side vane, *A'*, attached to the outer arm of the lever *b*, the wind-pressure acting against this vane acting as the rebutting force against 40 the pressure of the gears. This causes the side pressure upon the turn-table or rotary head at *c* to be opposed to the side pressure upon the turn-table at the inner end of the wheel-shaft, thereby effecting a balance or 45 equalization of forces and entirely overcoming the side draft.

It will be observed that the same principle is involved in each of the three forms illustrated, the only difference between them being that lever *b* is differently sustained or rebutted in each, but in all the lever is and must receive its support from some part independent of or not rigidly attached to the turn-table or revolving head.

50 As shown in Figs. 6 and 7, a stop, *a'*, limits the movement of the equalizer in one direction, while a spring, *a''*, (shown in Fig. 7,) holds the equalizer normally against the stop.

Referring now to Figs. 1 and 2, the construction of the wheel proper will be explained.

55 *L* indicates a skeleton hub or boss, which may be conveniently cast in one piece, and rendered malleable or not, as deemed advisable, and *M* indicates one of a series of cylindrical radial metal spokes, each preferably

formed of iron tubing, screwed into the hub or boss and held by a set-screw, *p*, against displacement, as indicated. The hub or boss is secured upon a tubular shaft, *F*, at some distance from the end thereof, and the spokes *M* are braced and stayed by rods *N*, extending from a point near the outer end of each spoke to a small hub or head, *O*, fixed at the front end of the shaft, the rods being formed with 70 eyes to encircle the spokes, upon which they are fixed by set-screws *q*, while their forward ends are passed through the hub or head *O* and secured by nuts, as shown.

The blades are formed with eyes to encircle 80 the spokes, the eyes being set to one side of the middle of the blades to cause the wind to act upon them and hold them normally at a given angle to the face of the wheel, and set out from the face of the blades to cause the 85 blades to swing naturally back of the spokes. The blades are thus eccentrically hung each way—that is to say, they are behind the spokes, and their middle lines are one side of the 90 spokes. By this construction three advantages are secured—the blades govern or adjust themselves more readily and perfectly, greater safety in a gale is insured, and they are quicker in regaining action after being suddenly lagged by overwork.

95 *Q* indicates a rod or pitman extending centrally through the tubular shaft *F*, and carrying at its forward end a piston or slide, *r*, fitting freely within the shaft, extending outward from the forward end thereof, and furnished at its front end with a rosette or circular head, as shown. From this head rods *R* extend to the blades *P*, one to each, with which they are connected at one side of the spoke at the narrower side of the wheel, each 100 rod being formed with an eye to encircle a stud or pin, *s*, secured in the inner end of the blade. Under this arrangement a movement 105 of the rod or piston in or out will cause the blade to be turned more or less flatly to the wind, a considerable outward movement of the rod causing the blade to be turned with its edge to the wind, so as to do away with the effect of the wind thereon, or nearly so. The piston *r* is loose upon the rod *Q*, being held 110 between a shoulder, *t*, and nut *u*, the latter being locked by a jam-nut, *w*.

The rod *Q* is moved in and out, as required, through the action of a governor, *U*, through the medium of other mechanism, more clearly 115 illustrated in Figs. 3 and 4.

To the inner end of the rod *Q* is attached a *U*-shaped yoke, *S*, either rigidly or by a swivel-joint, which yoke straddles a hub or boss, *T*, secured or formed upon the vertical shaft *I*, the yoke being of such width that its two arms cannot both be in contact with the hub at the same time. The yoke is moved laterally to cause one or the other arm of the yoke to bear against the hub or boss *T*, according to the 125 speed of the wheel and the consequent action of a ball-governor carried by the upper end of the 130

shaft I, the rod Q being of course moved in or out as the yoke is in contact with and acted upon by one or the other side of the hub T.

To thus control and move the yoke, I provide a sliding block or frame, V, carrying two rollers, v, which bear, respectively, upon the outer faces of the two arms of the yoke S, so that as the slide is moved in one direction one arm is pressed by one roll v into connection with the hub or boss T, and when the slide is moved in the opposite direction the other arm is similarly pressed into contact with the hub or boss by the other roller.

The yoke stands normally in such position that neither arm touches the hub or boss T, and consequently the blades of the wheels stand in their normal working position; but when the wheel exceeds a given speed the balls of the governor rising elevate the collar w, and with it one arm of an elbow-lever W, which is pivoted in a bracket, X, encircling the shaft, and connected with the block or slide V by bolts extending through slots in one of said parts, so that the block or slide may 25 move freely in a horizontal direction, but not vertically.

The block or slide V is in turn supported at one end by a bracket, Y, projecting inward from the shell C, the two parts being connected by a bolt passing through a slot in one of said parts to permit the free sliding motion of the block or slide, and at the other end by a flexible or elastic shouldered rod, Z, the end of which enters a hole or socket in the inner 35 side of the block. This latter support or its equivalent—a suspension-rod—permits a slight motion of the block in all directions, but serves to retain it normally in such position that neither of its rollers shall press the yoke 40 against the hub or boss T of shaft I.

When the wheel is at rest, the governor-balls drop down, forcing the yoke into contact with hub T at that side, which will cause an inward movement of the yoke or rod, and which 45 will bring the blades to their most effective working position, so that the wheel will soon act with its full power up to the limit beyond which it is deemed unwise to run it. As the wheel approaches such speed, and the shaft I rotates with proportionate rapidity, the balls of the governor rise and through the intermediate mechanism move the slide or frame V to its normal position, so that the yoke S is held out of contact with hub T, in which 50 position it remains until the balls of the governor again fall, or until raised, through an increase of the speed of the wheel, they move the slide in a direction to force the yoke into contact with that side of the hub or boss T 55 necessary to move the rod Q outward and turn the blades edgewise to the wind.

The head of the governor U is carried by a lever, from which a rod, y, extends down through the frame to permit the blades to be 60 set or controlled manually when desired.

The precise manner of mounting or sup-

porting block or frame V is not important, but, like other details, may be varied as desired.

It is not essential, though preferred, that the bar or shoe d be provided with rollers.

Having thus described my invention, what I claim is—

1. In combination with a geared windmill, an equalizing device consisting of a lever, b, pivoted to the rotary shell or turn-table of the mill and provided at its inner end with a bearing for the vertical shaft of the mill, and a bar or shoe pivoted to the outer end of said lever, and arranged, substantially as shown 80 and described, to press against the fixed cap or head of the tower or support.

2. In combination with cap B, rotary head or shell C, provided with vane G and wheel H, vertical shaft I, connected by gearing with 85 the wind-shaft of wheel H, and lever b, pivoted to the head C, and provided at its inner end with a bearing for the shaft I, and at the outer end with bar or shoe d, having rollers e, to press against the cap B, substantially as 90 shown and described.

3. In combination with a wind-wheel having pivoted blades, governing mechanism consisting of a governor carried by the driven shaft, a rod provided with a yoke straddling 95 a hub or boss on the driven shaft, and with a head connected by rods with the pivoted blades, and a slide connected with the governor and arranged to press against the yoke, substantially as shown and described, where- 100 by one or the other arm of the yoke is pressed against the hub or boss whenever the speed of the wheel rises or falls above or below a predetermined point, thereby causing the yoke and its rod to be moved in or out and to 105 turn the blades to take more or less wind, as required.

4. In combination with a wind-wheel having pivoted blades, a governor receiving motion from the wind-wheel, a shaft driven by 110 said wheel and provided with a hub or boss, a movable head connected with the pivoted blades, a yoke connected with said movable head and extending on opposite sides of the hub or boss of the driven shaft, and mechanism, substantially as described and shown, 115 connected with and actuated by the governor, for throwing the yoke into contact with one or the other side of the hub or boss, according to the rate of speed of the wheel.

5. The combination, substantially as herein described and shown, of wheel H, having pivoted blades P and tubular shaft F, rod Q, provided with head r, and yoke S, rods R, connecting the blades with head r, shaft I, provided with hub or boss T, and connected by gearing J K with shaft F, governor U, and slide V, connected with and adapted to be moved by the governor, said parts being constructed and arranged substantially as shown 125 and described.

6. In combination with a wind-wheel hav-

ing pivoted blades, a shaft driven by said wheel and provided with a hub or boss, a yoke straddling the hub or boss and connected with pivoted blades, a governor, a slide connected with the governor and adapted to press the yoke against the hub or boss, and a support for the slide, consisting of a bracket at one end and a swinging rod at the other end, substantially as shown and described.

10 7. In a geared windmill, an equalizer-lever,

b, pivoted to the rotary head or turn-table of the mill, and provided at its inner end with a box or bearing for the vertical shaft of the mill, and having its outer end abutted against a part of the mill independent of the turn-table, substantially as shown.

ISAAC P. CADMAN.
